UNITED STATES PATENT OFFICE.

HARRY BENWELL STOCKS AND JOHN RACKER WEBB, JR., OF MANCHESTER, ENGLAND, ASSIGNORS TO THE CLIMAX PATENTS LIMITED, OF MANCHESTER, ENGLAND.

PERCUSSIVE HAND-TOOL.

No. 845,905.

Specification of Letters Patent.

Patented March 5, 1907.

Application filed September 28, 1906. Serial No. 336,582.

To all whom it may concern:

Be it known that we, HARRY BENWELL STOCKS and JOHN RACKER WEBB, Jr., subjects of Great Britain, residing at 107 Barlow Moor road, Didsbury, Manchester, in the county of Lancaster, England, engineer, and 5 14 Tennis street, Old Trafford, Manchester aforesaid, engineer, respectively, have invented new and useful Improvements in Percussive Hand-Tools, Power-Hammers, and Similar Tools Actuated by Compressed Air, of which the following is a specification.

Our invention relates to percussive hand-tools, power-hammers, and similar tools actuated by compressed air in which a piston or tup reciprocates within a cylinder, as is 15 well understood.

Under our invention we use two continuous streams of air under pressure for the blow 20 and return stroke, and we also employ a valve governing the admission of motive fluid to the piston of the hammer, such valve having a small area on which motive fluid is constantly acting, tending to force the valve 25 over in one direction, and a large area on which motive fluid intermittently acts to move the valve at the required times in the contrary direction.

We are aware that the principle set out in 30 the preceding sentence is not novel; but the essential novel feature of our invention, in addition to the particular construction and operation of the valve and system of ports, consists in the employment of a continuous 35 stream of air under high pressure for the blow stroke and a continuous stream of air under low pressure for the return stroke, so that the hammer works economically and with an absence of vibration and shock or 40 jar.

We may under our invention construct the hammer so that the air under high pressure is admitted behind the piston for the whole 45 of the blow stroke, or with a modification in detail such air under high pressure may be cut off when the piston has made but a portion of its stroke, the remainder of the stroke being worked by the expansive power of the admitted fluid. We could also use either air 50 under high pressure or air under low pressure for constantly loading the smaller area of the valve governing the admission of motive fluid to the tool.

In the accompanying drawings, Figure 1 represents a sectional elevation on the line A 55 B, Fig. 2, of a percussive hand-tool constructed in accordance with our invention, in which the valve is loaded constantly on its smaller area with air under high pressure. Fig. 2 is a 60 sectional plan thereof. Figs. 3 and 4 are respectively sectional elevation and sectional plan of a similar hammer, but provided with an expansion-valve to cut off air under high pressure when the piston has made but a portion of its blow stroke. Figs. 5 and 6 are 65 sectional elevation and plan of a percussive hand-tool in which a single valve only is used loaded constantly on its smaller area with air under low pressure; and Figs. 7 and 8 are 70 similar sectional elevation and plan of a percussive hand-tool similar to Figs. 5 and 6, but provided with an expansion-valve.

It will be noted in the percussive hand-tools illustrated in the accompanying drawings like parts are similarly lettered to avoid 75 repetition of description of these parts.

We will refer first to Figs. 1 and 2, in which the valve is loaded constantly on its smaller area with air under high pressure. The tool consists of a cylinder *a*, in which is freely slideable a piston *b*, provided with an annular recess *c* at its rear end. The cylinder *a* is secured to the boss *d* of the handle *e* by means of a screwed nut *f*, bearing against a flange *g* on the inner end of the cylinder, the flange *g* 80 contacting with a disk *h*, interposed between the flange *g* and a valve-box *i*, contained in the boss *d* of the handle *e*. The mouth of the cylinder *a* is provided with a bush *j* to carry the end of a chisel *k* or other tool. The 85 meeting faces of the end of the valve-box *i* and the boss *d* of the handle *e* are formed to provide concentric annular recesses *m n*. A tube *o'*, conducting air under high pressure, is secured to the inlet *o* in the handle, and 90 another tube *p'* to conduct air under low pressure is connected at *p* to the handle. From *o* a passage *q* connects with the annular recess *m*, and a similar passage *r* connects 95 *p* with the recess *n*. Each of the passages *q r* is governed by a piston-valve *s*, slideable in a chamber *s'*, the lower end of which is closed by a screwed plug *s''*. A trigger *t* is mounted 100 on a fulcrum *u*, the trigger being disposed between the valves *s s'*. This trigger is provided with a horn *v*, through which and pro-

jecting from each side thereof is a cross-pin *w*, disposed on the top of the valves *s s*. Normally the air under pressure in the conducting-tubes is sufficient to maintain the valves *s s* in the elevated position shown in Fig. 1. When pressure is applied upon the valves *s s* by means of the trigger *t*, the valves are depressed, and communication is established between the passages *o p* and ports *q r*, so that air under high and low pressures is conducted to the annular grooves *m n*, respectively, the groove *m* containing air under high pressure and the groove *n* air under low pressure. In the valve-box *i* a distribution-valve *x* is fitted capable of a sliding movement to a certain extent. This valve *x* is formed hollow with exhaust-passages *y* formed therein. It is of two different diameters to form a shoulder *z*, and also an annular groove *2* is provided near the end in the smaller diameter. Ports are formed in the valve-box *i*, communicating with the high and low air-pressure recesses *m n*, with the valve *x*, and with ports leading to the front and rear of the piston *b*. As shown in Fig. 2, the piston *b* is at the inner end of its stroke and the valve *x* is in correct position to admit air under high pressure (assuming the valves *s s* to be depressed by the trigger *t*) to the back of the piston for the blow stroke. Air under high pressure is constantly acting on the small area *z* of the valve *x*, such air under pressure being admitted to the area *z* from the groove *m* via the ports *3* and *4*, forcing the valve *x* over into the position shown in Fig. 2. The reduced diameter of the valve *x* enables air under high pressure to pass to the port or ports *5* and from thence through the hole or holes *6* in the disk *h* to the back of the piston *b*, actuating the piston for the blow stroke, the residual air under pressure of the previous return stroke in front of the piston exhausting through the port *7* out of the aperture *8* at the inner end of such port *7*, uncovered by the valve *x* to the exhaust-passage *9* in the handle of the tool, and so to atmosphere. When the piston *b* is just attaining the end of its blow stroke, the annular recess *c* uncovers the entrance *10* to a port *11*, which port *11* is then put into communication with the cavity *m*, containing air under high pressure, by means of the port *3*, so that air under high pressure is admitted to the front or large area *12* of the valve *x*, over-coming the air under high pressure acting constantly on the small area *z* and moving the valve *x* into the position shown in Fig. 1. Air under low pressure can then pass from the recess *n* through the port *13* in the valve-box *i*, around the annular groove *2* in the valve *x* to the groove *13^a*, and by way of the port *8* to the port *7* through the hole *7^a* in the disk *h*, and so to the front of the piston *b*, returning the piston to the position shown in Fig. 2. On the return stroke of the piston *b*

residual air of the previous blow stroke is exhausted through the aperture or apertures *6* in the disk *h* and the port or ports *5* to the annular groove *14*, from which it passes through the exhaust-ports *y*, through the hollow valve *x* to the exhaust *9*, and so to atmosphere. To enable the air under high pressure acting constantly on the small area *z* of the valve *x* to return the valve *x* to the position shown in Fig. 2 for the next blow stroke, the port *11* is continued forward and is provided with an outlet *13^b* into the cylinder *a*. This outlet *13^b* is uncovered when the piston *b* is attaining the end of its return stroke, and the air under high pressure previously admitted to act on the large area *12* of the valve *x* exhausts into the cylinder *a*, bringing about such a reduction of pressure against the area *12* of the valve *x* that the air under high pressure constantly acting on the small area *z* is enabled to move the valve *x* over in the position shown in Fig. 2, and the described cycle of operations for the blow and return strokes is repeated. The hammer is automatically self-starting, for suppose when the air under different pressures is admitted by the valves *s s* the piston *b* should be in the position shown in Fig. 1, while the valve *x* is in the position illustrated by Fig. 2, the air under high pressure would pass round the annular groove *c* in the piston *b* and be conducted by the port *11* to the front or large area *12* on the valve *x*, forcing it back to the correct position shown in Fig. 1 to admit air under low pressure for the return stroke. On the contrary, should the piston *b* be ready for the blow stroke, as shown in Fig. 2, and the valve *x* be in the position indicated in Fig. 1 air under high pressure, which constantly acts on the small area *z*, would as soon as admitted by the valve *s* force the valve *x* forward to the correct position illustrated by Fig. 2.

With a hammer constructed as described the air under high pressure is admitted behind the piston *b* during the whole of the blow stroke; but we may provide means, as illustrated in Figs. 3 and 4, for cutting off the air under high pressure when the piston *b* has made but a portion of its stroke, so that the remainder of the stroke would be completed by the expansive action of the admitted air under high pressure. To effect this, we provide the valve-box *i* with an expansion-valve *15*, consisting of a ring of metal with equal areas *15^a* *15^b* and formed with an internal annular recess *16*, the valve *15* being slidable fluid-tight on a seat prepared for it in the valve-box, as illustrated. Air under low pressure from the port *13* acts constantly against the area *15^b* of the valve *15*, as will be seen from an inspection of Fig. 3. As shown in Fig. 4, the valve *x* has been moved forward by air under high pressure acting constantly, as explained, on the small area *z*, and the valve *15* has also been moved forward by the air

under low pressure. The air under high pressure is thus admitted from the ports 3 4 to the groove 5^a, and by a port or ports 20 to the recess 16 in the valve 15 and a port or ports 5 21 to ports 22 through holes 23 in the disk *h*, and thus behind the piston *b*. When half or any other predetermined portion of the blow stroke has been completed, a hole 17 in the cylinder (see Fig. 3) is uncovered by the piston *b*, and the air under high pressure behind the piston enters a port 18 and is conducted by a passage 19 in the disk *h* to the front area 15^a of the expansion-valve 15, forcing it back against the air under low pressure acting on the area 15^b into the position shown in Fig. 3, and thus cutting off the supply of high-pressure air to the back of the piston *b*. The remainder of the stroke is thus completed by the expansive force of the admitted air under high pressure. The air of the previous return stroke in front of the piston *b* is exhausted through the port 7 to atmosphere through the exhaust-outlet 9, as already described with reference to Figs. 1 and 2. For the return stroke the valve *x* is moved backward into the position shown in Fig. 3 by high-pressure air admitted to the front or large area 12 of the valve via the ports 3, 10, and 11, as previously described when referring to Figs. 3c 1 and 2. Air under low pressure is then admitted through the port 13 and annular groove 2 to the annular recess 13^a, to the ports 8 and 7, to the front of the piston *b*, returning the piston for the next blow stroke. On the return stroke of the piston *b* the residual air-pressure of the previous blow stroke behind the piston *b* is swept out through the holes 23 in the disk *h*, ports 22, to the ports 21, and from thence through the holes *y* to the interior of the valve *x*, and so to atmosphere through the exhaust-outlet 9, as clearly seen in Fig. 3.

It has already been explained, when referring to Figs. 1 and 2, how the air under high pressure acting on the large area 12 of the valve *x* is reduced sufficiently to enable the valve *x* to be forced forward by the air under high pressure acting constantly on the small area *z* of the valve in readiness to admit air under high pressure behind the piston *b* for the blow stroke and to exhaust the forward end of the cylinder *a*. In the construction shown in Figs. 3 and 4 it is necessary to also move the expansion-valve 15 forward again into the position indicated in Fig. 4. This is effected by providing the port 18 with an outlet 19^a into the cylinder *a*, such outlet being uncovered when the piston *b* has completed its inward stroke, so that air under high pressure admitted to the front area 15^a of the expansion-valve is reduced in pressure by exhausting into the forward end of the cylinder *a*, which at this instant is placed in communication with the atmosphere by the forward movement of the valve

x, as previously explained. Air under low pressure which is constantly admitted behind the area 15^b of the expansion-valve 15 via the port 13 is thus enabled to force the expansion-valve forward to enable it to admit high-pressure fluid behind the piston *b* for the blow stroke. 7c

We do not confine ourselves to the use of air under high pressure for constantly loading the small area of the distribution-valve *x*, as the air under low pressure used for returning the piston *b* within the cylinder *a* may be employed, as illustrated in the construction, Figs. 5 to 8. In Figs. 5 and 6, which we will first deal with, no expansion-valve is used, 75 the distribution-valve *x* admitting air under high pressure behind the piston *b* throughout the entire blow stroke. For the return stroke the valve *x* and piston *b* are in the relative positions shown in Fig. 5. The 80 valve *x* is formed with two annular grooves 2 and 2^a. Air under low pressure passes from the annular groove *n* along the port 13, around the annular groove 2^a in the valve *x* to the groove 13^a, and to the port 7 to return 85 the piston. Air previously supplied behind the piston is exhausted through the holes 6 in the disk *h* and ports 5 to the annular groove 14, and from thence through the holes *y* to the interior of the valve *x*, and from 90 thence to atmosphere by the exhaust 9. As the piston attains the end of its return stroke the port 11 permits air under pressure on the large area 12 of the valve *x* to exhaust into the cylinder *a*, and from thence by a hole 23 95 to atmosphere. This reduces the pressure on the large area 12 of the valve *x* to atmospheric, or thereabout, and enables air under low pressure acting constantly on the shoulder or small area *z* of the valve *x* to move the 100 valve forward in the position shown in Fig. 6. Thus air under high pressure can pass from the groove *m* through the ports 3 and 4, around the annular groove 2 to the port 5, and thus behind the piston for the blow 105 stroke. The air under pressure of the previous stroke in front of the piston exhausts through the ports 7 and 8 to the exhaust 9, and so to atmosphere. When the blow stroke is completed, air under high pressure 110 is conducted from the port 3 around the annular recess *c* in the piston *b* through the ports 10 11 behind the large area 12 of the valve *x*, forcing it backward into the position 115 shown in Fig. 5 to admit air under low pressure in front of the piston *b* for the return stroke. 120

Figs. 7 and 8 show a similar hammer to Figs. 5 and 6, but having an expansion-valve 15 constructed and applied in manner similar 125 to that in Figs. 3 and 4. As shown in Fig. 7, the return stroke of the piston *b* and the exhausting of air under pressure behind the piston is effected as described with reference to Fig. 5 and can be readily followed. When 130

the piston *b* has been returned to the position shown in Fig 8, air under pressure in front of the area 15^a of the expansion-valve 15 and air under pressure acting on the large area 12 of the valve *x* exhausts into the cylinder *a* through the ports 11 18, and from thence to atmosphere through the hole 23 in the cylinder, so that air under low pressure acting on the rear area 15^b of the expansion-valve 15 5 and also on the small area *z* of the distribution-valve *x* is enabled to move both these valves forward into the position shown in Fig. 8. The cylinder *a*, behind the piston *b*, is then open to admit air under high pressure 10 for the blow stroke, as will be apparent. Air under pressure in front of the piston *b* is exhausted to atmosphere on the blow stroke through the ports 7, 8, and 9. When a portion of the blow stroke has been effected, the 15 air under high pressure admitted to the cylinder *a* behind the piston passes through the ports 17, 18, and 19 to the front area 15^a of the expansion-valve 15, forcing it backward to the position shown in Fig. 7 and cutting off 20 the supply of air under high pressure, so that the remainder of the stroke is completed by the expansive pressure of the air under high pressure admitted behind the piston.

It will be understood that the motive fluid 30 for the blow stroke may be air under any desired pressure in excess of the pressure used for the return stroke and the air under low pressure such as will be sufficient to promptly return the piston in the cylinder in readiness 35 for the blow stroke.

The drawings show the invention applied to a percussive hand-tool, but the invention may be used with larger power-hammers actuated by air under pressure.

40 We declare that what we claim is—

1. In percussive hand-tools, power-hammers and similar tools in which a piston or tup is reciprocated to and fro within a cylinder, inlet-ports conducting two continuous 45 streams of air, one under high pressure for the blow stroke and one under low pressure for the return stroke, in combination with a distribution-valve having two unequal areas, the small area being constantly acted upon by air under pressure and the large area being intermittently acted upon by air under pressure substantially as described.

2. In percussive hand-tools, power-hammers and similar tools in which a piston or tup is reciprocated to and fro within a cylinder, inlet-ports conducting two continuous 55 streams of air under pressure, one under high pressure for the blow stroke and one under low pressure for the return stroke, in combination with a distribution-valve having two unequal areas, the small area being constantly acted upon by air under pressure and the large area being intermittently acted upon by air under pressure, with means for 60 cutting off admission of air under high pres-

sure when the piston has made but a portion of its stroke substantially as described.

3. In a percussive hand-tool, power-hammer or similar tool, a cylinder, a piston slideable within such cylinder, inlet-ports for two continuous streams of air under different pressures, a valve-box, a hollow distribution-valve of unequal diameters slideable in such valve-box formed with exhaust-passages, unequal areas formed on such valve to form differential pressure areas, ports to conduct constantly air under pressure to the smaller pressure area of the valve, ports governed by the piston to conduct intermittently air under pressure to the larger area of the valve, 70 an exhaust-port to atmosphere, ports formed in the cylinder communicating with the distribution-valve and valve-box, substantially as described.

4. In a percussive hand-tool or the like, a cylinder, a piston slideable within such cylinder, inlet-ports for two continuous streams of air under different pressures, a valve-box, a hollow distribution-valve of unequal diameters slideable therein formed with exhaust-passages, unequal areas formed on such valve to form differential pressure areas, ports to conduct constantly air under pressure to the smaller area of the valve, ports governed by the piston to conduct intermittently air under pressure to the larger area of the valve, an expansion-valve slideable in the valve-box, ports to conduct air under low pressure constantly to one area of the expansion-valve, ports governed by the piston 90 to conduct air under high pressure intermittently to the other area of the expansion-valve, an exhaust-port to atmosphere, ports formed in the cylinder communicating with the valves, and valve-box, substantially as 100 described.

5. A power-hammer consisting of a cylinder, means for carrying a tool in the mouth of the cylinder, a piston slideable in the cylinder, a recess formed in the rear end of such piston, a handle secured to the cylinder, a valve-box within such handle, a disk secured between the cylinder end and the valve-box, a hollow distribution-valve of unequal diameters slideable within the valve-box, exhaust-passages in such valve and an annular recess, unequal areas on the valve to form two differential pressure areas, an exhaust-passage communicating with the hollow distribution-valve and to atmosphere, inlet-ports in the handle for two continuous streams of air under high and low pressure, throttle-valves governing such inlets and means for operating the throttle-valves, ports to conduct constantly air under high pressure to the smaller area of the distribution-valve to actuate the valve in one direction, ports governed by the distribution-valve to conduct air under high pressure behind the piston for the blow stroke, ports 115 120 125 130 135

governed by the distribution-valve to exhaust air in front of the piston to atmosphere, ports governed by the piston to conduct air under high pressure at the end of the blow 5 stroke around the annular recess in the rear of the piston to the larger area of the distribution-valve to actuate the valve in the contrary direction, ports governed by the distribution-valve to conduct air under low 10 pressure in front of the piston for the return stroke, ports governed by the distribution-valve to exhaust air behind the piston to atmosphere, and ports governed by the piston to exhaust air under pressure acting on the 15 larger area of the distribution-valve, at the end of the return stroke substantially as described.

6. A power-hammer consisting of a cylinder, means for carrying a tool in the mouth 20 of the cylinder, a piston slideable in the cylinder, a recess formed in the rear end of such piston, a handle secured to the cylinder, a valve-box within such handle, a disk secured between the cylinder end and the valve-box, 25 a hollow distribution-valve of unequal diameters slideable within the valve-box, exhaust-passages in such valve, and an annular recess, unequal areas on the valve to form two differential pressure areas, an exhaust-passage communicating with the hollow 30 distribution-valve and to atmosphere, inlet-ports in the handle for two continuous streams of air under high and low pressure, throttle-valves, governing such inlets and 35 means for operating the throttle-valves, ports to conduct constantly air under high pressure to the smaller area of the distribution-valve to actuate the valve in one direction, an expansion-valve slideable in the valve- 40 box, equal pressure areas at each end of such expansion-valve, ports to conduct constantly air under low pressure to the rear of such expansion-valve, ports governed by the distribution-valve to conduct air under high pressure behind the piston for the blow 45 stroke, ports governed by the piston to conduct air under high pressure admitted behind the piston to the front pressure area of the expansion-valve to move the valve backward and cut off the admission of air under 50 high pressure behind the piston when the piston has made but a portion of the blow stroke, ports governed by the distribution-valve to exhaust air under pressure in front of the piston to atmosphere, ports governed 55 by piston to admit air under high pressure around the recess in the rear of the piston to the larger area of the distribution-valve to slide the valve backward, ports governed by the distribution-valve to admit air under 60 low pressure to the front of the piston for the return stroke, ports governed by the distribution-valve to exhaust air behind the piston to atmosphere, and ports governed by 65 piston to exhaust air under pressure acting on the larger area of the distribution-valve, and on the front area of the expansion-valve at the end of the return stroke, substantially as described.

In testimony whereof we have signed our 70 names to this specification in the presence of two subscribing witnesses.

HARRY BENWELL STOCKS.
